(57) **CLAIM**

The ornamental design for an electronic identification device, as shown and described.

DESCRIPTION

FIG. 1 is a perspective view of an electronic identification device, showing my new design;

FIG. 2 is a top view thereof;

FIG. 3 is a front view thereof;

FIG. 4 is a bottom view thereof;

FIG. 5 is a back view thereof;

FIG. 6 is a right view thereof; and

FIG. 7 is a left view thereof.

FIG. 8 is a perspective view of an electronic identification device with side device, showing my new design;

FIG. 9 is a top view thereof;

FIG. 10 is a front view thereof;

FIG. 11 is a bottom view thereof;

FIG. 12 is a back view thereof;

FIG. 13 is a right view thereof; and,

FIG. 14 is a left view thereof.

Broken lines shown in the drawings illustrate portions of the electronic identification device, and form no part of the claimed design.
